UNITED STATES PATENT OFFICE.

FRANK CONRAD, OF PITTSBURGH, PENNSYLVANIA, ASSIGNOR TO WESTINGHOUSE ELECTRIC AND MANUFACTURING COMPANY, A CORPORATION OF PENNSYLVANIA.

IGNITION MECHANISM.

1,248,459.

Specification of Letters Patent.

Patented Dec. 4, 1917.

Application filed April 3, 1914. Serial No. 829,191.

To all whom it may concern:

Be it known that I, FRANK CONRAD, a citizen of the United States, and a resident of Pittsburgh, in the county of Allegheny and 5 State of Pennsylvania, have invented a new and useful Improvement in Ignition Mechanisms, of which the following is a specification.

My invention relates to ignition mechanisms, and it has particular reference to such mechanisms as are adapted to be employed in connection with dynamo-electric machines for furnishing current for igniting the explosive charges of gas engines.

15 My invention has for its object to provide a mechanism of the above indicated character which is simple and inexpensive in construction and in which certain parts are combined to form a unitary structure.

20 In the construction of magnetos and other types of generators that are designed to furnish high-tension current for ignition purposes, it is the usual practice to employ an induction coil and a high-tension distributor which connects the secondary winding of the induction coil to the cylinders in the order in which they are to be fired. These devices are separate and distinct and, in 25 some cases, are a considerable distance apart.

30 The terminals of the devices are connected by insulated conductors that are detachably fastened to the terminals. In practice, considerable trouble has resulted from the grounding of the conductors or from breaks 35 in the circuits caused by loose connections.

I provide an arrangement in which the stationary portion of a distributor and the casing of an induction coil are constructed of an integral mass of molded or plastic insulating material. The structures thus combined, form an end casing or a cover plate for the dynamo-electric machine. The conductors which connect terminals of the induction coil to those of the distributor are 45 embedded in the casing, the connections being made permanent at the place of manufacture.

50 My invention is illustrated in the accompanying drawing in which Figure 1 is an end view, in elevation, of an end plate of a dynamo-electric machine constructed in accordance with my invention. Fig. 2 is a

sectional view on line II—II of Fig. 1. Fig. 3 is a view, in longitudinal section, of a portion of a dynamo-electric machine embodying my invention.

55 My invention is shown as employed in connection with a small generator of current suitable for ignition or other purposes. The generator 1 comprises a field magnet 2, an armature 3 and an armature shaft 4. A pinion 5, that is mounted upon the forward end of the armature shaft 4, meshes with a gear wheel 6 that is secured to one end of a short shaft 7, the latter being rotatably mounted, by means of suitable ball 65 bearings 8, in the frame 9 of the generator.

A circular insulating block 10, that is secured upon the outer face of the gear wheel 6, has embedded in it a conducting tube 11, 70 the axis of which is inclined to the axis of the gear wheel 6 and the block 10, and the inner end of which is provided with an exposed extension 12 to form a central contact member upon the outer face of the 75 block 10. The tube 11 serves as a receptacle and guide for a brush 13, a spring 14 for resiliently pressing the brush outwardly being interposed between the inner end of the brush and the bottom of a recess in the block 80 8 that constitutes an extension of the opening in the tube 11.

85 The parts just described are inclosed by a cover block 15, that is clamped or otherwise suitably secured to the end face of the 90 generator frame and is preferably composed of molded insulating material, it being provided with an inclined or frusto-conical inner face against which the outer end of the brush 13 bears. A plurality of conductors 95 16, that are embedded in the cover plate 15, are provided, at their outer ends, with terminals 17 for connection to any suitable ignition device. The conductors 16 terminate, at their inner ends, in enlargements or segments 19 that have uniformly spaced contact faces that are flush with the inclined inner face of the cover 15 and are interposed in the path of movement of the brush 11 to be engaged in succession thereby. A 100 conductor 20, that is also embedded in the cover 15, is connected to a tube 22 that serves as a receptacle and guide for a brush 23. A helical compression spring 24, that is in-

terposed between the inner end of the brush 23 and the bottom end of the tube 22, causes the brush to resiliently engage the contact member 12.

5 The cover 15 is provided, at its upper end, with a recess or opening 25 to be occupied by an induction coil 26. The primary windings of the induction coil are connected to sleeve members 27 that are embedded in the 10 cover 15, by means of conductors 28 that are embedded also in the cover 15. The conductor 20, which is connected to the central contact member 12, is connected to the secondary winding of the induction coil 15 in any suitable manner (not shown).

In the construction of the cover 15, the conductors 20 and 28 are placed in their proper relative positions within the mold previous to the pouring of the insulating material. 20 After the molded cover 15 has cooled, the induction coil is placed within the recess 25 and the conductors 20 and 28 are connected to the respective terminals of the coil. The coil is then sealed in position 25 by means of insulating material indicated at 29 which is poured over the coil 26 and, also, by means of a cover 30 of insulating material similar to that of which the cover 15 is constructed. The cover 15 is held in 30 position by two screws 31 (only one being shown) which are connected to and insulated from the end plate 9. The screws 31 serve, also, as terminals for the primary winding of the coil 26.

35 In the operation of the ignition mechanism, the terminals 31 will be connected, in any suitable manner, to the source of supply of current and the terminals 17 are connected in proper order to the cylinders of 40 a gas engine. High-tension current will then traverse the conductor 20, tube 22 and brush 23 to the central contact member 12 upon the block 10 and from thence to the brush 13 which successively engages and 45 conducts current into the lower ends of the conductors 16 and thereby distributes current to the engine cylinders in their proper sequence.

50 It will be noted that I have provided a mechanism in which a number of closely related parts have been combined to form a unitary structure. By means of this arrangement, all danger of short circuits or of grounding the conductors which connect the 55 induction coil to the distributor, is avoided. Also, there is no danger that the conductors will be loosened at their points of connection by the vibration incident to the operation of a gas engine of an automobile.

60 I claim as my invention:

1. In an ignition mechanism, the combination with a dynamo-electric machine, of an insulating end casing therefor, an induction coil permanently and completely in- 65 closed by said casing, terminals for said coil,

and conductors for connecting said terminals to said coil, said conductors being surrounded by said insulating material.

2. In an ignition mechanism, the combination with a distributor comprising a stationary portion, of an induction coil, a casing for said coil, said casing being integral with the stationary portion of said distributor, and means for electrically connecting said coil to said distributor. 70

3. In an ignition mechanism, the combination with a dynamo-electric machine, of an end casing therefor having a recess, an induction coil in said recess, a distributor comprising a stationary portion that is integral with said casing, and means for electrically connecting said coil to said distributor. 75

4. In an ignition mechanism, the combination with a dynamo-electric machine, of an end casing therefor formed of insulating material and provided with a recess, an induction coil permanently inclosed in said recess, and conductors connected to the terminals of said coil and embedded in said insulating material. 80

5. In an ignition mechanism, the combination with a dynamo-electric machine, of an end casing therefor formed of insulating material and provided with a recess, an induction coil permanently inclosed therein, a distributor comprising a stationary portion integral with said casing, and means for electrically connecting said coil to said distributor. 95

6. In an ignition mechanism, the combination with a dynamo-electric machine and a casing member therefor formed of insulating material, of an induction coil inclosed by said casing, terminals carried by said casing, a distributor comprising a stationary portion that is integral with said casing, and conductors embedded in said insulating material for connecting the coil to said terminals and to said distributor. 100

7. In an ignition mechanism, the combination with a dynamo-electric machine, of an end-casing therefor formed of insulating material and provided with a recess, an induction coil in said recess, a distributor comprising a rotatable portion and a coacting stationary portion that is integral with said casing, and a conductor embedded in said casing for connecting said coil to said distributor. 110

8. In an ignition mechanism, the combination with an ignition distributor having a stationary portion, of a coil, and a casing for said coil that is integral with said stationary portion. 120

9. In an ignition mechanism, the combination with an ignition distributor having a stationary portion of insulating material, of a coil, and a casing for said coil that is integral with said stationary portion. 125

10. In an ignition mechanism, the combi- 130

nation with an ignition distributer having a stationary portion of insulating material, of a coil, and an insulating casing for completely inclosing said coil that is integral 5 with said stationary portion.

11. In an ignition mechanism, the combination with an ignition distributer having a stationary portion of insulating material, of a coil, a casing for said coil that is integral 10 with said stationary portion and an elec-

trical conductor embedded in said casing for connecting said coil to said distributer.

In testimony whereof, I have hereunto subscribed my name this 27th day of March, 1914.

FRANK CONRAD.
